UNITED STATES PATENT OFFICE.

MICHEL SCHÉNI, OF PARIS, FRANCE.

KNITTING MACHINE.

Application filed March 24, 1927, Serial No. 178,105, and in France March 29, 1926.

The object of this invention is to provide a knitting machine characterised by the fact that it embodies a combination of the Jacquard loom and a two-bed united-needle 5 warp machine.

It will be recalled that the standard knitting machine of the type indicated, sometimes called a "Rachel" loom comprises two beds furnished with self-acting needles arranged vertically and adapted to produce 10 knitted fabrics with one or a plurality of warp thread laps coming from one of several beams or rollers and led by guides or reeds which place the threads in the needles of 15 the two beds by means of lateral shifting movements in a direction perpendicular to the needles.

The reeds being fixed on their bars, all 20 to one and the same bar must necessarily undergo, all of them, all the same shifting movements either to protrude together with the needles from one or both beds, or to pass between two rows of needles (behind the 25 needles) without making a stitch, like threads that weave, and such threads are then invisible on the surface of the cloth. The result is that production of coloured 30 patterns is confined within rather narrow limits. As a matter of fact any possible shifting of the threads, while operating alternately the various groups or laps, can form only geometrical figures, squares, rectangles, 35 lozenges and zig-zags more or less regular and intersecting, but can never form, say, a spiral line nor any pattern with varied designs, as is possible with a weaving loom fitted with a jacquard device, or with jacquard-equipped knitting frames which do 40 not work on the principle of warp-arranged threads.

My invention consists in applying the jacquard device to a knitting mechanism of the two-bed united-needle warp type, hereafter termed for convenience a "Rachel" loom, 45 in order to obtain on said Rachel loom far more varied patterns, each thread being able to be changed from any group or lap to another by the action of the jacquard device.

In order to make the characteristic features of the invention more clearly understood, a preferred embodiment thereof has been illustrated in the accompanying drawing, in which:

Figure 1 is a view, partly sectional and partly in elevation, showing a double reed

and the combs; in this Figure the needles and their support are also seen.

Figure 2 is a plan view of the combs.

Fig. 3 is a side elevation of Fig. 1, but 60 showing also the mechanism for operating the movable combs.

According to the invention, instead of securing the reeds directly on the bars which receive their lateral drive from the drum through a chain having links of different heights, I use a double reed 1 having two long flexible shanks (Figure 1), which reed is mounted as follows: The usual square main support carrying the whole reed bar 65 mechanism is formed by two plates 2 connected together at their ends only. The body of the reed passes between these two plates and rests thereon at *a* and *b*. The reeds are guided and kept within the gauge 70 of the loom by a lattice of steel blades 4 mounted in the leads 3, each blade having a curved edge *c* which prevents the next reed from getting up and compels it to shift horizontally under the influence of a bell-crank lever subsequently described. The leads 3 are secured, say by screws, on the outer sides of plates 2 and are removable so as to allow a reed to be changed or replaced. The blades 4 are further provided with pairs 75 of depending feet *c'*, *c''* (Figure 6) which are welded to the leads 3, and the latter, together with said blades, contribute to give to plates 2 the rigidity required, the whole 80 forming a block adapted to rock on its axle 85 just like the square support of the common loom.

The jacquard device that I use is of current pattern, of the same kind as the one for the weaving loom, with a number of 95 heddles corresponding to the number of needles contained in one bed of a "Rachel" loom of current gauge of width. It will act on the reeds in the following manner:

Each steel blade 4 has an ear 5 (Figures 100 1 and 6) provided with a hole adapted to receive spindle 6, on which ear pivots a bell crank lever 7 the thickness of which is equal to the spacing between two blades 4. The body of the reed has the form of a *T* 105 and its horizontal bar 1' is provided with a recess or depression 1² to receive the rounded end of the short arm 7' of lever 7. The heddle 8 coming from the jacquard device located above the loom and not shown 110 on the drawing, is hooked to bell crank 7 through eyelet 9. The bell cranks 7 are

kept in position α (down) by a rod, not shown, constituting a weight, located on top, or by a spring suitably positioned or else by a press mechanism; and when said bell 5 cranks are rocked into this position α , the reeds occupy the position $e-f$. When, under the action of the jacquard device, one of the bell cranks 7 is lifted up to position γ the reed will be shifted to the position 10 e^1-f^1 . In Figure 1 the two shanks of the reed are seen to be engaged a little above their ends g and h in the combs or sleys 10, 10^a and 11. These combs take the place of the ordinary reeds and are suitably suspended, at both ends, from arms extending 15 to the main support from which they derive the rocking motion necessary to lead the reeds through the needles. Said combs are composed of the rigid bars 12, 12^a and 20 13 which receive the leads cast on the steel blades that form the teeth of the combs 10, 10^a and 11. The middle comb 11 is a double one; that is to say the steel blades form teeth on both its sides. On the outer rigid 25 bars 12 and 12^a are located caps 14 and 14^a with holes arranged in two rows to lead the threads i and j to the eyes in the ends g and h of the shanks; but said bars may be given any other suitable shape, for instance, instead of being formed of cast lead sections, they may consist of reamed teeth.

In Figure 2, combs 10, 10^a and 11 are shown in plan. The ends of the combs on the drum side carry thrust blocks with adjustable screws 15, 15^a and 16 corresponding to the faces of the bolts 17, 17^a and 18 extending to the link chain drum 19, the latter being driven by gearing 20. Owing to the different heights of the chain links, 40 said combs are therefore caused to shift horizontally and laterally over one or several needles so as to guide the ends g and h of the reed shanks carrying the weaving threads i and j and to place said threads around needles K and L in order to make 45 them form stitches or between and behind the needles to shoot the weft. The movements of the combs are, of course, transmitted to the shank ends of the reeds, and said 50 shanks, owing to their flexibility, can readily yield and follow such movements.

When the jacquard device has brought a reed to position e^1, f^1 , the end g of the left-hand shank will be engaged in the left-hand 55 side of the middle comb 11, and the end h of the right-hand shank will be engaged in the right-hand comb 10^a. If, on the contrary, a reed is not shifted by the jacquard but remains in its normal position e, f , the 60 left-hand shank end g will be in the left-hand comb 10 and the right-hand shank end h will be in the right-hand side of comb 11. I thus obtain two groups of selected 65 reeds, equal in number, the first group being constituted by the shanks of the reeds

engaged in the middle double comb 11 and bound, all of them, to make the same shifting movements. The second group is constituted by the shanks engaged in the outer combs 10 and 10^a which will make altogether the same shifting movements as imparted by the link chain, which movements will be different from those of the first group. Supposing all the reeds are threaded and shank ends g carry threads differing 70 in colour from the threads carried by shank ends h , each needle on the loom will have at its disposal two threads of different colours and, through the action of the jacquard, each thread can be shifted to the other group or to another comb after each row of stitches. When the jacquard device removes one thread from a group, said thread is automatically replaced by the thread carried by the other shank of the same reed, so that each group always forms a complete lap of threads.

It should be noted that combs 10 and 10^a are superimposed over comb 11 (Figure 2) so that they cannot rub against one another, 90 and the blades forming the teeth are shaped as required in order that passage of the reed shanks from one comb to another will be quite reliable and that the shanks will begin to engage into the new comb before leaving the previous one.

I will now describe the method of operation of such a loom. Threading is the same as for normal work on an ordinary loom with two reed bars, the threads coming from the rollers or from the beams located at the top of the loom being passed through the holes of the caps 14 and 14^a and thence through the holes of the reed shanks. The shanks g carry threads differently coloured from those carried by shanks h , but if desired, the two shanks of the same reed can carry threads of different colours, or even threads of one and the same colour. I may also modify at will the colours all over the 100 width of the loom.

Certain reeds will be shifted by the action of the jacquard device, according to a given pattern, after each row of stitches, and the threads will occupy four different 115 positions: the two middle positions in comb 11 may serve to make the stitch, that is to say comb 11 will have imparted to it (by means of the drum links) the shifting required in order that all the threads carried by the reed shanks g and h engaged in said comb 11 may make stitches with the needles of the two beds K and L and form rows of two-coloured or plural coloured stitches. The two outer positions wherein the reed shanks 120 are engaged in combs 10 and 10^a will serve to place the threads in weft between and behind the needles so as to be invisible on the surface of the fabric, and the weft can be made on several needles over the distance 130

required in order that there may be compensation as to thread consumption between the threads that shoot the weft and those which make the stitch and come from one and the same roller or beam. In fact, the shanks of the reeds being sufficiently pliant and the combs quite independent of one another, nothing prevents imparting to the outer combs 10 and 10^a a lateral shifting long enough to shoot the weft over a distance of several needles. Equal or even absorption of the threads is, therefore, ensured. The beams are prepared as usual. When the teeth of the double comb 11 make stitches with the needles of the front bed L they imprison the threads standing in weft on comb 10^a, and when the double comb 11 makes stitches with the needles of the rear bed K said comb imprisons the complementary weft threads on comb 10.

Combs 10 and 10^a can, as well, be actuated by the drum chain motions to make stitches and, vice versa, the middle comb 11 can be actuated to shoot the weft; said combs may even alternate operations in making one and the same piece of fabric.

I do not intend my invention to be limited to the embodiment hereabove described, and I reserve the right to modify in any suitable manner the form and the arrangement of the various parts without being deemed to depart from the scope of my invention.

I claim as my invention:

1. A knitting machine, comprising a series of reeds each having two long, pliant thread-carrying shanks; a needle-bed for coaction with the reed shanks; a jacquard device for shifting the reeds perpendicularly to the needle-bed so as to bring into operation the

thread carried either by the one shank or 40 the other of a reed; and combs cooperative with said shanks to guide and flex them laterally over one or more needles.

2. A knitting machine, comprising a series of reeds each having two long, pliant thread-carrying shanks; a needle-bed for coaction 45 with the reed shanks; a jacquard device for shifting the reeds perpendicularly to the needle-bed so as to bring into operation the thread carried either by the one shank or 50 the other of a reed; and combs cooperative with said shanks to guide and flex them laterally over one or more needles; said combs including a double intermediate comb, and two single combs at opposite sides 55 thereof.

3. A knitting machine, comprising a series of reeds each having two long, pliant thread-carrying shanks; a needle-bed for coaction with the reed shanks; and a jacquard device 60 for shifting the reeds perpendicularly to the needle-bed so as to bring into operation the thread carried either by the one shank or 65 the other of a reed.

4. A knitting machine, comprising a series 65 of reeds each having two long, pliant thread-carrying shanks; a two-bed united-needle warp mechanism cooperative with the ends 70 of the shanks and including a jacquard device for shifting the reeds perpendicularly to the needle-beds so as to bring into operation the thread carried either by the one shank or the other of a reed; and combs cooperative with 75 said shanks to guide and flex them laterally over one or more needles.

In testimony whereof I affix my signature.

MICHEL SCHÉNI.
